CLAIM

The ornamental design for a nasal dilator, as shown and described.

DESCRIPTION

FIG. 1 is a perspective view of a first embodiment of a nasal dilator showing my new design;

FIG. 2 is a top plan view thereof;

FIG. 3 is a front view thereof, the rear view being a mirror image thereof;

FIG. 4 is a right side view thereof, the left side view being a mirror image thereof;

FIG. 5 is a bottom plan view thereof;

FIG. 6 is a perspective view of a second embodiment of a nasal dilator showing my new design;

FIG. 7 is a top plan view thereof;

FIG. 8 is a front view thereof, the rear view being a mirror image thereof;

FIG. 9 is a right side view thereof, the left side view being a mirror image thereof; and,

FIG. 10 is a bottom plan view thereof.

(Continued)

The broken line showing of human facial features is directed to environment and is for illustrative purposes only; the broken lines form no part of the claimed design.

1 Claim, 2 Drawing Sheets
